UNITED STATES PATENT OFFICE.

CARL WINKLER, OF BERNE, SWITZERLAND.

MELTING POT PARTICULARLY FOR STEREOTYPING METAL.

Application filed August 13, 1920. Serial No. 403,363.

To all whom it may concern:

Be it known that I, CARL WINKLER, a citizen of the Swiss Republic, residing at Berne, in the Swiss Republic, have invented a new 5 and useful Improved Melting Pot Particularly for Stereotyping Metal, of which the following is a specification.

In the last few years there is a tendency to construct melting furnaces for stereotyping metal, particularly those used for casting stereotype plates, of such dimensions that several moulds can be simultaneously fed. This certainly effects an economy of space and simplifies attendance, but in practice it will be found that disturbances, in most cases, are due to defects in the melting pot, which, owing to the comparatively high, and frequently fluctuating, temperature of the metal, is highly strained. If the printing establishment has only one melting pot for all moulds, the entire concern must stop working until the damage is repaired.

By my invention this drawback is overcome in the case of a melting furnace adapted to feed several moulds by dividing the pot into several independently operable units having a common frame. When one of these units becomes defective, it is still possible to keep the concern going with one 30 or more of the remaining units, without much loss of time, provided the size of the furnace is adapted to the requirements of the particular establishment.

Preferably the furnace is so constructed 35 that on heating one of the units the waste gases from this unit can be used to heat at least one other unit. This is of special importance in such cases in which one unit of the furnace is used for small outputs several 40 hours before the main work of the day commences, for which several (or all) units are employed, in order to accelerate the work, because then the preparation for the principal work of the day is shortened and facilitated.

In the accompanying drawing a twin furnace constructed according to the invention is shown by way of example.

Fig. 1 is a vertical section of the improvement and

50

Fig. 2 is a horizontal section.

This furnace is designed to feed two moulds *a*, *b*, into which the molten metal flows, on opening the cocks *c*, *d*, under the head of the metal in the melting pots *e*, *f*. 55 Each of these melting pots constitutes a unit with one of the furnaces *g*, *h*, which, like the melting pots, can be operated independently of each other. Both units, however, are surrounded by the common frame *i*. The 60 flues *k*, *l* of the furnaces *g*, *h* are separated from each other by a partition *m*, in which is provided a door *n*, adapted to be turned into the positions shown in dotted lines (Fig. 2), in order to conduct the gases from 65 one furnace through the flues of the other furnace in passing to the chimney *o*.

With this arrangement each unit can be operated independent of the other, whilst, if desired, the unit not in use, can be preliminarily heated for later by the waste gases.

What I claim and desire to secure by Letters Patent of the United States is:—

1. A melting furnace for stereotype metal, comprising two melting pots each having a 75 valve controlled outlet, two adjoining furnaces, one wall of each of which forms a wall of a pot, flues for the furnaces, and a valve for establishing communication between the said flues.

80

2. A melting furnace for stereotype metal, comprising two melting pots, each having a valve controlled outlet, two adjoining furnaces, one wall of each of which forms a wall of a pot, a casing surrounding the melting pots and provided with a transverse partition, said casing and partition forming flues surrounding the melting pots, and a valve in said partition.
